MATHIAS PIER, OF HEIDELBERG, GERMANY, ASSIGNOR, BY MESNE ASSIGNMENTS, TO STANDARD-I. G. COMPANY, OF LINDEN, NEW JERSEY, A CORPORATION OF DELAWARE

APPARATUS FOR CARRYING OUT THE DESTRUCTIVE HYDROGENATION OF CARBONACEOUS MATERIAL

Application filed August 11, 1928, Serial No. 299,124, and in Germany August 30, 1927.

For carrying out reactions at high pressures and temperatures, especially in the presence of hydrogen or gases containing or supplying the same, it has already been proposed to employ apparatus constructed of highly alloyed steels, or apparatus comprising an inner vessel of chemically resistant materials, such as iron free from carbon, or silver and the like, and an outer shell adapted to stand pressure and provided with openings for the escape of hydrogen issuing from the inner vessel.

I have now found that in the destructive hydrogenation of carbonaceous materials, such as coals, tars, oils and the like, which process is described and claimed in the Australian Patent No. 1217/26, the range of pressure and temperature hitherto employed may be substantially increased by using jacketed apparatus, that is to say a double walled apparatus, the outer wall of which, or the inner wall exposed to the chemical action of the gases or both of the said walls of which are constructed of chromium alloy steels.

The employment of an outer vessel of chromium alloy steel has the advantage that the duration of service of the inner vessel is prolonged to a remarkable extent, and in particular even at high pressures and very high temperatures. The use of chromium alloy steel for the inner vessel, exposed to chemical action gives the very substantial advantage that the losses of gases, such as hydrogen by diffusion are extremely low. The advantages of the said apparatus are still further increased when both vessels are made of chromium alloy steels. Inasmuch as the various parts of the apparatus can be easily detached and renewed and only the inner vessel is subjected to considerable wear and tear, a substantial reduction in running costs, having regard to the usually high price of chromium alloy steels, is effected compared with the case of an apparatus constructed wholly in one part.

It is of particular advantage if the chromium alloy steels employed are adapted as far as possible to suit the conditions imposed on them. For example, the inner vessel may be made of a chromium alloy steel with high

powers of resistance to chemical influences, or the outer shell may be made of a chromium alloy steel highly resistant to mechanical influences or impervious to hydrogen, in particular at high temperatures, or the two vessels may be constructed of the most suitable materials. The chemically resistant materials are often extremely expensive, and as the amount required, in the arrangement herein described, is reduced to a minimum, a considerable saving is effected, coupled with maximum strength. The outer shell may be closed, or may be provided with openings to permit the hydrogen, for example, diffusing through the inner vessel, to escape.

For example, the inner vessel, with high powers of chemical resistance, may consist of high grade chromium alloy steels, such as alloys of iron with chromium and nickel, chromium and vanadium or chromium and tungsten, or of a steel containing 20 per cent of chromium, 7 per cent of nickel and 0.25 per cent of carbon and the outer vessel, which has to stand the pressure may consist of any other suitable material. Conversely, the outer tube, taking up the pressure, may be made of a high-grade chromium alloy steel particularly resistant to mechanical influences and the inner vessel of any other suitable material. Under certain circumstances, the outer shell of chromium alloy steel impervious to hydrogen, may also take the form of a thin envelope which after the manner, to some extent, of a hydrogen proof coating, surrounds the thicker pressure resisting inner shell of ordinary material. In this case, although a corrosive contact occurs between the hot hydrogen and the inner iron shell, diffusion through the inner shell is considerably retarded, so that this system has a far longer working life than one without an outer shell of special steel. When both parts of the jacketed apparatus consist of chromium alloy steel, the herein specified special steels best adapted for the particular purposes, are used.

The accompanying drawing represents in a diagrammatic manner a vertical cross section of a destructive hydrogenation apparatus suitable for carrying out the invention.

On the drawing:

Reference numeral 1 represents a high pressure reaction vessel composed of two concentric readily separable shells, 20 and 21, the 5 inner shell 20 being formed of a chromium alloy steel resistant to attack by sulfur and hydrogen. The thickness of this shell is such that it is permeable to hydrogen under the conditions prevailing in the reaction vessel 10 when in use. The outer shell 21, has materially thicker walls which are resistant to pressure. This shell may be composed of ordinary steel but preferably is made up of the same material as the inner shell 20 in order 15 to resist attack by the hydrogen passing through the inner shell. The walls of the outer shell 21 are preferably provided with numerous openings 24 which permit escape of hydrogen diffusing through the thin inner shell. 20 In this way the hydrogen seeping through the inner shell is prevented from forcing the two shells apart, which action would seriously impair the vessel 1.

The open ends of the inner and outer shells 25 20 and 21 are closed by pressure resisting caps 25 and 26, bolted to flange members 27 and 28, which surround the ends of the outer shell. Preferably a heat insulating medium 29 is located between said caps and flange 30 members.

Said caps also serve to fasten the inner and outer shells together, in a manner in which they can be readily separated, as will be seen from a reference to the drawing. This result is attained by bending or crimping the 35 ends of the inner shell over the ends of the outer shell, the caps 25 and 26 then securely clamping the crimped ends of the inner shell against the ends of the outer shell.

40 Cap 25 at the lower end of the vessel is provided with an inlet pipe 22 by which the reacting materials, that is, hydrogen and carbonaceous materials are fed into the vessel 1, while cap 26, at the top of the vessel, is provided with an outlet pipe 23 for the removal 45 of gaseous products formed in the reaction.

What I claim is:

An apparatus for destructively hydrogenating distillable carbonaceous materials containing sulfur, with hydrogen, comprising a vessel composed of two readily separable concentric shells, the inner having relatively thin, 50 hydrogen permeable walls of a chromium alloy steel resistant to attack by sulfur and hydrogen, the outer having relatively thicker walls which possess a high resistance to pressure and which are also composed of a chromium alloy steel resistant to hydrogen and sulfur attack, said outer wall having 55 openings therein to permit escape of the hydrogen diffusing through the thin inner shell.

In testimony whereof I have hereunto set my hand.

MATHIAS PIER.
